UNITED STATES PATENT OFFICE.

WALTER EVERETT MOLINS, OF LONDON, ENGLAND.

FILLING MACHINE AND THE LIKE FOR USE IN THE AUTOMATIC PACKING OF CIGARETTES AND OTHER ARTICLES.

Application filed January 15, 1923. Serial No. 612,706.

To all whom it may concern:

Be it known that I, WALTER EVERETT MOLINS, a citizen of the United States of America, residing in London, England, have 5 invented certain new and useful Improvements in and relating to Filling Machines and the like for Use in the Automatic Packing of Cigarettes and Other Articles, of which the following is a specification.

10 This invention relates to improvements in the closing apparatus of filling machines employed in the automatic packing of cigarettes and other articles into slide and shell or like packets or cartons.

15 The object of the invention is to provide means whereby a packet or carton which has received an insufficient number of cigarettes or the like is closed or partially closed in a manner which readily indicates that its contents are incorrect.

20

It has already been proposed to use electrical devices whereby a bell, or other electrical detector, is operated when a packet or carton is incorrectly filled but with such 25 methods, it has been necessary for the operator to keep observation upon the particular packet or carton during the subsequent operations of the filling machines, in order to ensure its ultimate separation from the 30 correctly filled packets or cartons.

According to the present invention, the inner portion or slide of the packet or carton with the cigarette or the like therein, is passed under a brush or the like before it is 35 delivered to the apparatus for closing the outer portion or shell thereon. This arrangement is such that if the slide portion is insufficiently filled, the gap caused by the missing contents will always occur at the 40 same side of the slide. The device which closes the shell on to the slide is provided with a suitably mounted pawl or like member, adapted to fall into the aforesaid gap when the slide is presented, preventing the 45 complete closing of the shell over the slide.

In the subsequent operation of the closing device, the carton is thus closed with the usual flap of the slide portion outside the shell instead of inside same, so that the 50 defectively filled carton can easily be detected and separated from the other filled cartons delivered by the machine.

It will be understood that the above described apparatus is particularly, but not 55 exclusively, adapted for use with machines

constructed according to the specification of United States application Serial No. 479,912, filed 2nd June, 1921.

To enable the invention to be fully understood it will now be described by reference 60 to the accompanying drawings in which the invention is shewn as applied to a machine of the kind described in the above mentioned specification. In the drawings:

Fig. 1 is a side elevation of the closing 65 apparatus of the machine,

Fig. 2 is a front view thereof, and

Fig. 3 is a plan view.

Fig. 4 is a view similar to Fig. 1 but shewing the parts in a different position, 70

Figs. 5 and 6 are views of details of the machine and

Figs. 7 and 8 are views of packets in different stages of closure.

In the example illustrated the packets 75 comprising an inner slide already inserted in an outer shell are continuously passing through the machine in the direction of the arrow 1, Fig. 3 and are carried on a conveyor as described in the aforesaid specifi- 80

The packets are closed by an arm *a* rocking about a pivot *b* in the known manner and in the present instance, the arm is adapted to operate on two packets simultaneously, each packet being closed in two stages. A closing piece *c* is mounted on the lower end of arm *a* stepped as shewn best in Figs. 3 and 6 at *c*², *c*³, each step being adapted to engage a shell *c'* when the 85 arm is swung inwards. With this arrangement, at each inward swing of the arm, the step *c*² closes a packet to the extent indicated at 2, Fig. 6, while the step *c*³ completes the closure of a packet which has previously been partially closed by the step *c*² as shewn at 5, Fig. 6. The packets are moving continuously and the operation of the arm *a* is also continuous, being suitably timed to co-operate with the movement of the packets in a known manner.

The mechanism for indicating an improperly filled packet is as follows:

Attached to the arm *a* is a spring controlled pawl *d* which operates on the end of a bent plate *e* pivoted at *f* in a bracket carried on a flat plate *g*. The plate *g* is hinged at *m* in a block *n* secured to the machine bed and carries a series of brushes *p* from its underside. The plate *e* is bent as shewn

(Fig. 1) its lower end *h* being bent downwardly and provided with a projecting tongue *k*. A stop *x* is also provided bearing against the plate *g* and a spring *y* arranged to hold the plate normally in its raised position.

A bent detecting finger *r* is pivotally mounted on the hinge *m* and is pressed downwardly by a light spring *s*, a pin *t* being fitted at the bend in the finger. This pin *t* engages a slot in a lever *u* pivoted at *f*, one end of the lever having a point *v* which is preferably hardened. A notched plate *w* is provided on the lower end of arm *a*.

The operation of the above described mechanism is as follows, the packets being assumed to be in the position shewn in Fig. 6:—

20 On each inward or closing swing of the arm *a*, the pawl *d* engages the plate *e* and pushes it over on its pivot until the pawl trips, the plate *e* then being returned to its original position by spring *y*.

25 The result of this action is to cause the end *h* to move sharply up and down, and during its downward movement the end *h* presses on the flap 4 of the slide (Fig. 4) and allows the shell to pass easily over same.

30 Referring more particularly to Fig. 5 which shews a section across an improperly filled slide. It will be noticed that only nine cigarettes are shewn in the packet, which is intended to hold ten. As the packet moves 35 in the direction of the arrow beneath the plate *g*, the brushes *p* sweep the four cigarettes of the top row towards the rear edge of the slide leaving a space at the leading edge.

40 When this packet comes under the detecting finger *r* the plate *e* has already moved downwards carrying with it the tongue *k* which has been acting as a stop. The finger *r* then drops under gravity and the pressure of spring *s* and as there is an empty space in the leading end of the packet, the finger drops therein.

45 As a result of this action, the point *v* of lever *u* is raised to such an extent that it engages the notch in plate *w* on arm *a* and stops further inward swinging of the arm *a* (Fig. 4). This arm *a* is operated through means which allow a yielding movement when movement of the arm is restrained to 55 prevent damage to the machine. When this restraint of the arm *a* occurs, as the packet moves into position to be engaged by step *c* of the arm (Fig. 6) the flap 4 of the slide springs up of its own accord as it passes 60 from beneath the end *h* of the plate *e* (Fig. 7), the arm *a* moving away from the packet again and returning to complete the closure. Thus when the arm *a* completes the closure on the imperfect packet in step *c*, the flap 4 of this packet will be on the out-

side of the shell enabling the operator to detect the faulty packet and remove same (Fig. 8).

A properly filled packet will not be affected in any way as the detecting finger *r* 70 will rest on the cigarettes and is thus prevented from falling further and the end *v* of the lever *u* will not be raised to meet the notched plate *w*.

A straight closure piece may be used instead of the stepped piece *c* arranged to operate on a single packet closing it in one motion. This latter arrangement is particularly effective in dealing with large size 75 cartons.

The plate *g* being hinged, may be readily lifted for inspection purposes.

It will be understood that the invention may be applied to filling machines of other types, and also that the articles packed may 85 be other than cigarettes.

For example, the invention may be applied to a machine for filling paper packets as described in the specification of United States application Serial No. 477,202, filed 90 13th June, 1921, in which case the detecting finger such as *r* entering a space due to a missing article may cause the top folding of the packet to be interfered with, either through interference with the packet folders 95 or by tearing the packet or marking it conspicuously in some such manner.

Having thus described the nature of the said invention and the best means I know of carrying the same into practical effect, 100 I claim:—

1. Apparatus for use with automatic filling and packeting machines for the purpose of indicating an improperly filled packet comprising a detecting member adapted to enter the improperly filled space in a packet to prevent the proper closure of the packet. 105

2. Apparatus for use with automatic filling and packeting machines for the purpose of indicating an improperly filled packet comprising in combination, a detecting member adapted to enter the improperly filled space in a packet to prevent the proper closure of the packet and means for ensuring that the space in a packet due to improper filling occurs always in the same 110 relative position in each packet.

3. Apparatus for use with automatic filling and packeting machines for the purpose of indicating an improperly filled packet comprising in combination an oscillating member for closing the shell of a packet over a filled slide, a detecting finger normally resting on the contents of the slide and means for depressing the flap of a slide in such a manner that when operating on an incorrectly filled slide the flap will be depressed on the outside of the shell when the latter is closed completely over the slide. 115

4. Apparatus for use with automatic fill-

- ing and packeting machines for the purpose of indicating an improperly filled packet comprising in combination, an oscillating member for closing the shell of a packet 5 over a filled slide, a detecting finger normally resting on the contents of the slide, means for depressing the flap of a slide, an operative connection between the oscillating member and the detecting finger, and a stop member connected to the detecting finger, the arrangement being such that in the case of an improperly filled packet, the detecting finger falls into the unfilled space therein, bringing the stop member into position 10 to arrest the closing motion of the oscillating member.
5. Apparatus for use with automatic filling and packeting machines comprising in combination a travelling conveyor for the 20 filled packets, sweeping members arranged above the conveyor and in contact with the articles in the slide of the packet, an oscillating closure member, a detecting finger, a member for depressing the flap on a slide, a 25 stop member, and connecting means between the detecting finger and stop member, so arranged that the entry of the detecting finger into an unfilled space in a slide causes the 30 closing motion of the closure member to be arrested.
6. Apparatus for use with automatic filling and packeting machines comprising in combination a closure member, a detecting

member, a flap depressing member, a stop member and operative connections whereby 35 an improperly filled packet is closed with the flap of the slide untucked in the shell of the packet.

7. Apparatus for use with automatic filling and packeting machines comprising in 40 combination a pivoted closure arm, a spring held pawl on said arm, a bent plate pivoted on a bracket, a flap depressing tongue on the lower end of the plate, a spring normally holding the plate in a raised position, a 45 pivoted detecting finger, a pivoted stop lever linked to the detecting finger and means on the closure arm for engaging the stop member.

8. Apparatus for use with automatic filling and packeting machines comprising in 50 combination, a pivoted closure arm, a spring held pawl on said arm, a bent plate pivoted on a bracket, a flap depressing tongue on the lower end of the plate, a spring normally 55 holding the plate in a raised position, a pivoted detecting finger, a pivoted stop lever linked to the detecting finger, means on the closure arm for engaging the stop member, a travelling conveyor for the packets and 60 sweeping members arranged above the conveyor and in contact with the articles in the slide of the packet.

In testimony whereof I have signed my name to this specification.

WALTER EVERETT MOLINS.
